CLAIM

The ornamental design for an agricultural machine armrest control console, as shown and described.

DESCRIPTION

FIG. 1 is a front view of an agricultural machine armrest control console of the present design;

FIG. 2 is a top view thereof;

FIG. 3 is a rear view thereof;

FIG. 4 is a side view thereof;

FIG. 5 is an opposite side view thereof;

FIG. 6 is a bottom view thereof; and,

FIG. 7 is a perspective view thereof.

The dashed lines shown in the figures represent portions of the agricultural machine armrest control console that form no part of the claimed design.

1 Claim, 7 Drawing Sheets
